UNITED STATES PATENT OFFICE

ALBERT E. R. SPEIDEL, OF EDGEWOOD, RHODE ISLAND

DESIGN FOR A BRACELET CHAIN

Application filed March 28, 1931. Serial No. 39,274. Term of patent 3½ years.

To all whom it may concern:

Be it known that I, ALBERT E. R. SPEIDEL, a citizen of the United States of America, residing in Edgewood, county of Providence, State of Rhode Island, have invented a new, original, and ornamental Design for a Bracelet Chain, of which the following is a specification, reference being had to the accompanying drawings, forming a part thereof.

Fig. 1 is a top plan view of a bracelet chain, showing my new design; and Fig. 2 is a section on line 2—2 of Fig. 1, of the same. A feature of the invention is the plain surface within the border.

I claim:

The ornamental design for a bracelet chain, substantially as shown.

ALBERT E. R. SPEIDEL.
